(57) **CLAIM**

The ornamental design for a display screen with icon, substantially as shown and described.

DESCRIPTION

FIG. 1 is a front view of a first embodiment of a display screen with icon showing the new design; and, FIG. 2 is a front view of a second embodiment thereof. The black shading represents a contrast in appearance. The broken line showing of the display screen in all figures forms no part of the claimed design.

1 Claim, 2 Drawing Sheets

FIG. 1

FIG. 2
